UNITED STATES PATENT OFFICE

115,803

DESIGN FOR A RESTAURANT BUILDING OR SIMILAR ARTICLE

Roland L. Stickney, New York, N. Y., assignor to J. B. Judkins Company, Merrimac, Mass., a corporation of Massachusetts

Application February 4, 1939, Serial No. 82,787

Term of patent 7 years

To all whom it may concern:

Be it known that I, Roland L. Stickney, a citizen of the United States residing at New York, in the county of New York and State of New York, have invented a new, original, and ornamental Design for a Restaurant Building or Similar Article, of which the following is a specification, reference being had to the accompanying drawing, forming part thereof, in which the figure is a perspective view of a restaurant building showing my new design, the right hand end of the building being identical to the left hand end shown in the drawing and the rear wall being plain except for necessary doors and windows.

I claim:

The ornamental design for a restaurant building or similar article, as shown and described.

ROLAND L. STICKNEY.
